UNITED STATES PATENT OFFICE.

FRANKLIN MELVIN WHITE, OF TOLEDO, OHIO, ASSIGNOR OF ONE-HALF TO JOSEPH ATKINSON, OF TOLEDO, OHIO.

WINDOW-VENTILATOR.

1,224,818.

Specification of Letters Patent. Patented May 1, 1917.

Application filed May 16, 1916. Serial No. 97,979.

To all whom it may concern:

Be it known that I, FRANKLIN M. WHITE, a citizen of the United States, residing at Toledo, in the county of Lucas and State of Ohio, have invented certain new and useful 5 Improvements in Window-Ventilators; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to new and useful improvements in ventilators for windows and consists of a simple and efficient device of this nature having various details of construction, combinations and arrangements of 20 parts which will be hereinafter fully described, shown in the accompanying drawings and then specifically defined in the appended claim.

My invention is illustrated in the accompanying drawings, in which:—

Figure 1 is a plan view showing the application of my ventilator to the window.

Fig. 2 is a vertical sectional view.

Fig. 3 is a cross sectional view on line 3—3 30 of Fig. 2.

Reference now being had to the details of the drawings by letter, A designates the frame of a window and B are headed pins or members fastened to the inner faces of the 35 frame. Angular flanged ventilator end pieces, designated respectively by letters C, have angled slots F in the edge thereof and adapted to engage said headed members to hold said end pieces by gravity.

40 H designates a sheet of any suitable material which is recessed away as at I at its lower corners and the lower portion of each

flange of an end piece is bent upon itself at J to receive said sheet of material near its lower end. The portion intermediate the recesses is adapted to engage the lower part of the sill, while the upper edges of the recess come flush with the face of the sill, as shown in the vertical sectional view of the drawings. The upper portion of the sheet H is slotted at N, and O is a screw passing through an aperture Q in said flange and said slot and each screw is provided with a winged nut T, forming means for securely holding the ventilator sheet in place.

In operation, if desired, it will be noted that the front portion of the ventilator may be removed independent of the end pieces by simply unscrewing the set screws and drawing out the front portion of the ventilator sheet.

What I claim to be new is:—

In a window ventilator, end pieces secured to the frame of a window, each end piece having a flange extending at right angles 35 with relation to the end pieces, the lower end of each flange extending upwardly to provide a pocket, the upper end of each flange having a slot, a deflecting sheet having its lower corners cut away to 70 provide shoulders and an intermediate extended portion, the shoulders adapted to engage within the pockets, bolts carried by the upper portion of the deflecting sheet, 75 said bolts adapted to engage within the slots, and means on the bolts for clamping the sheet and flanges together.

In testimony whereof I hereunto affix my signature in presence of two witnesses.

FRANKLIN MELVIN WHITE.
